UNITED STATES PATENT OFFICE.

FERN S. HEGGELUND, OF DEADWOOD, SOUTH DAKOTA.

DESIGN FOR A DOLL.

Application filed July 25, 1923. Serial No. 6,864. Term of patent 7 years.

To all whom it may concern:

Be it known that I, FERN S. HEGGELUND, a citizen of the United States of America, residing at Deadwood, in the county of Lawrence and State of South Dakota, have invented a new, original, and ornamental Design for a Doll, of which the following is a specification, reference being had to the accompanying drawing, forming a part hereof.

In the drawing:

Fig. 2 is a side elevation of the same.

I claim:

The ornamental design for a doll, as shown,

Mrs. FERN S. HEGGELUND. [L. S.]
